UNITED STATES PATENT OFFICE.

JAMES EDWIN TARBOX, OF LYNN, MASSACHUSETTS.

WATCHMAN'S TIME-DETECTOR.

SPECIFICATION forming part of Letters Patent No. 293,684, dated February 19, 1884.

Application filed June 27, 1883. (No model.)

To all whom it may concern:

Be it known that I, JAMES EDWIN TARBOX, of Lynn, in the county of Essex, of the Commonwealth of Massachusetts, have invented 5 a new and useful improvement in registers for indicating the time or times when a watchman may visit a room or a mill, my apparatus, or parts of it, being also useful for various other purposes; and I do hereby declare the same 10 to be described in the following specification and represented in the accompanying drawings, of which—

Figure 1 is a top view of it without its cover. Fig. 2 is a longitudinal section of it. Fig. 3 15 is a transverse section of it. Fig. 4 is a top view, Fig. 5 an end elevation, and Fig. 6 a transverse section, of the mechanism used for depressing the lever of the marker-supporting disk. Fig. 7 is a side view, and Fig. 8 a 20 vertical section, of the marker. Fig. 9 is a side view of the wheel O, hereinafter described.

The apparatus is to produce on a tablet or piece of paper markings, to denote the times when a person or watchman may have attended to a duty assigned to him to perform, 25 for at each of such times being obliged to effect by the mechanism a downward movement of the marker, to cause it to mark the tablet or sheet of paper.

30 In the drawings, A denotes the box or case of the apparatus, such box having within it a partition, a, dividing it above and parallel to its bottom. Within the space b, beneath the said partition, is a clock-movement, B, whose minute-hand arbor is shown at c as projecting up through and above the partition, and a metallic disk, C, arranged as represented. This disk rests on an annulus, C', supported 35 by a lever, D, so as to be movable vertically with the said lever, toward and away from a sheet, E, of paper placed on the top of the partition. On this sheet of paper a circle is drawn, and divided by radial lines into twelve equal sectors, the circle being concentric with the disk C. An arm, d, pivoted to the arbor c at its upper part, so as to be capable of being turned vertically, has journaled on it a screw, D', provided with a wheel, f, to rest 40 at its periphery upon the disk C. As the arbor is revolved by the clock-movement, such

arbor carries around with it the screw, which at the same time is revolved by the wheel f, which in turn is revolved by running upon the disk. Screwed loosely upon the screw is the pendulous or gravitating marker E, which 55 has a small arm, g, extending from it, as represented. This marker is a sector of an ellipse in form, and is to have within it a chamber for holding ink, and such chamber has an opening at the middle of the arc of the sector, 60 through which opening the ink can pass, a wick or stuffing of such nature being arranged in the opening for the purpose of absorbing the ink and preventing it from improperly escaping. On the marker being depressed upon the paper, a dot or mark will be made thereon by it, the said marker; but if the marker is kept in contact with the paper, such marker will turn on the screw, so as to arrest the marking of the paper. The marker, by its 65 weight when off the paper, hangs on the screw and does not revolve upon it. The screw revolves within the marker, however, and thereby causes the marker, while being carried with the screw around in the circle on the paper, to gradually approach the center of such circle. From this it will be seen that the marker in its traverse in the circle moves entirely around it every hour, and in a helix, 70 and it should be twelve hours in passing from the circumference of the circle to or near to that of the disk C. One of the radial lines of the circle, in the part of it between the disk and the circumference of such circle, is divided into twelve equal parts, and numbered from 75 1 to 12, as represented, to indicate the hours of the traverse of the marker.

There is to the lever D a spring, h', for forcing it upward after each depression of it. From the above it will be seen that if, at stated 80 times during the twelve hours, a person may be required to depress the said lever, a mark on the paper will be made every time he may so move the lever, the times when the marks may have been so produced being indicated by 85 their positions on the paper. Within the case is a mechanism for depressing the lever. This mechanism may be thus described: A shaft, I, supported in suitable standards, K K, so as to be able to freely revolve therein, has fixed on 90 100

it, at one end of it, a toothed wheel, L, to act on the lever D. This wheel has eight teeth. There is also fixed on the shaft a ratchet-wheel, M, having eight teeth. A pawl, N, 5 pivoted to one of the standards, engages with the ratchet-wheel. Furthermore, there is fixed on the shaft four toothed wheels, O, O', O², and O³, each having two teeth, arranged and formed as shown in Fig. 9. These wheels are 10 alike in shape, and each has fulcrumed on the shaft one of four levers, P, P', P², and P³. Each of these levers is provided with a spring-pawl, h, to bear against the periphery of its wheel. To the lower end of each lever one 15 end of a spiral spring, S, is fastened, the other end of such spring being secured to the bottom of the case. Wires R, R', R², and R³ extend from the levers through one side of the case, and where outside of the case are bent in 20 circles or provided with knobs, to enable them (the said wires) to be pulled to move their levers, to cause the pawls thereof to turn the wheels O, O', O², and O³. These wheels are 25 so arranged on their shaft that, on the wires R, R', R², and R³ being pulled in succession, the shaft will be caused at each pull to make one-eighth of a revolution. If it is the duty 30 of a person to pull these wires successively during a given period of time—as one hour, for instance—so long as he does this marks will be regularly made on the paper; but should he fail to pull any one of these wires at

the proper time, no mark will be made by the marker, and, consequently, by the absence of such mark, it will be shown that he did not 35 perform his duty. So, were he to pull the wire out of time, there would be no mark made. He must pull the wires in regular rotation in order for marks to be made.

There may be a greater or less number of 40 the wheels of the series O, O', &c., the number of operative levers with their springs and pawls and pulling-wires being varied accordingly.

I claim—

1. The register, substantially as described, consisting of the time-piece movement, the lever and its spring, the tablet or sheet, marked as explained, the disk, the arm, the screw and its wheel, and the marker, all being arranged 50 essentially and to operate as set forth.

2. The combination, with the register, substantially as described, of the mechanism, essentially as explained, for depressing the lever of such register, such mechanism consisting of the shaft I, its toothed wheel L, series of toothed wheels O, O', O², and O³, and their series of operative pawls and levers, provided with springs and pulling-wires, all being as 55 represented.

JAMES EDWIN TARBOX.
